FRANK D. PEARNE, DECEASED.

RADIOTRANSFORMER.

Application filed March 16, 1925. Serial No. 15,965.

This invention relates mainly to radio receiving sets and more especially to amplifying transformers and accessories adapted for use in audio-current circuits.

The main objects of the invention are to provide an improved form of means for amplifying weak alternating currents, including especially such currents which are of audio frequency; to provide an improved form of transformer device adapted for use in or in connection with radio receiving sets; to provide an audio-transformer of improved form adapted to provide greater amplification than the ordinary or fixed reluctance form of sound current transformer, or the form having a substantially unvariable permanent field; to provide a multiplex regenerative transformer of improved form and characteristics for the purpose stated; to provide an improved form of transformer adapted for automatic variable reluctance in operation; to provide such a transformer having dynamo-electric action; and to provide in combination therewith a sensitive pressure rheostat attachment adapted and arranged to supplement the inductive action of the primary winding.

Several illustrative embodiments of this invention are shown by the accompanying drawings, in which:

Fig. 1 is a schematic diagram of a simple crystal receiving set, with one embodiment of the improved transformer device in the audio circuit.

Fig. 2 is a similar view somewhat elaborated with a modified form of circuit connections including a three coil induction device besides the main transformer equipment in the audio circuit.

Fig. 3 is a diagram of a two tube receiving set with one embodiment of the transformer operably interposed between the tubes.

Fig. 4 is mainly a side elevation of a simple form of transformer such as represented in the diagram of Fig. 1.

Fig. 5 is a side elevation of a modified form of transformer in which the essential parts of the movable member are duplicated and arranged symmetrically about a central transverse pivotal axis, relative to which the stationary member is also symmetrically disposed.

Fig. 6 is a fragmentary view of a further modification of the transformer showing the

vibratory armature part formed with four core arms in spider-like arrangement with coil spools thereon, instead of one arm and one spool or two arms and two spools, as represented by the two preceding figures, respectively, the view being substantially as taken on a horizontal section line such as at 6-6 on Fig. 5, the terminal plate being removed.

Fig. 7 is a fragmentary horizontal sectional view of the device of Fig. 6, substantially as on a section line at 7-7 on Fig. 5.

Fig. 8 is merely a diagram of connections for the coils on the four pole vibrator of Fig. 6.

Fig. 9 merely illustrates the idea that the coil or coils may be carried by the stationary yoke instead of by the vibratory armature of a transformer substantially such as shown by Figs. 1 to 4.

Fig. 10 shows an embodiment wherein the magnetic pull tending to minimize the air gap is opposed by gravity.

Fig. 11 shows an embodiment wherein the magnetic pull tending to minimize the air gap is opposed by the resilience of a single-piece magnetic circuit core element.

Referring to the drawings, a very simple embodiment of this invention is shown by the crystal detector receiving circuit diagram of Fig. 1. Here the aerial is connected to the ground G through an inductance I and a variable condenser C in parallel therewith, as usual, and the crystal detector C. D. is connected in series with the primary winding A on the vibratory armature 1 of the transformer 2, between the aerial and ground. Said armature is provided with a secondary winding B leading to a loud speaker L. S., whereby the sounds transmitted to the primary winding are amplified by a single step-up transformer action. This action is augmented by the coincident variations in the air gap 3 and consequent reluctance changes.

In order to further amplify the sound currents, a tertiary winding C is connected in series with a variable pressure rheostat 4 and a battery 5. The vibratory responsiveness of the device and variation of the air gap are attained by providing for relative movement of the poles N and S according to variations in flux from the normal. In this instance the armature member 1 is pivoted to the yoke Y at Y' and is urged, against

the magnetic pull, to swing the pole N away from pole S, so as to enlarge the gap 3, for which purpose a spring 1' is adjustably set by a screw 1" according to specific needs.

Referring to Fig. 2, the equipment and connections are like those of Fig. 1, except that a second transformer or induction coil T is interposed between the windings on armature 1 and loud speaker. Here the 10 transformer T has two primaries, 6 and 7, one of which is connected to the secondary winding B of armature A and the other is connected to the circuit of the tertiary winding C, the secondary of transformer T being 15 connected directly to the loud speaker.

In order to show how this invention may be used in a tube set, reference is had to Fig. 3. Here the apparatus at the left of transformer 2 is all connected in accordance 20 with the usual or any well known practice, including preferably a vario coupler V. C., a variable condenser C and the first tube or detector 8. Here the audio transformer circuit, including the plate P and filament F 25 of the first tube 8 and the B-battery, is connected in series with the primary winding A of the transformer 2. The secondary winding B of said transformer is connected to the grid circuit of the second tube 9. The 30 tertiary winding C is connected directly across the A battery, with the pressure rheostat 4 and control switch 10 in series. From the foregoing, in view of the connections shown in Fig. 3, the operation of the 35 second tube in energizing the loud speaker will be apparent. Here we have the direct step-up transformer action between the primary and secondary coils A and B. The 40 dynamo-electric effect of the primary winding in actuating the vibrator 1 strengthens the step-up effect. This effect is still further supplemented by the tertiary winding C which is energized from the A battery, in accordance with the armature vibration 45 effect on the pressure rheostat 4. The windings and mechanical features are designed and arranged to coordinate with one another so as to effect a maximum degree of transformer step-up amplification. The secondary 50 winding B, thus highly energized, has a powerful effect on the grid of the second tube 9 with corresponding results on the plate circuit thereof which leads to the 55 loud speaker.

Referring next to the matter of specific forms of structure and design for the transformer and its accessories, attention is directed to Figs. 4 to 11 illustrating a number of different embodiments, each embodying the main generic ideas characterizing this invention, and each having also peculiar merits respectively according to various specific requirements.

The equipment shown in Fig. 4 is similar 60 to that shown in the right hand part of

Fig. 1, but includes more mechanical detail. Here the yoke Y is represented as mounted on an insulating base 12 and the spring 13 for adjusting the position of the armature 14 is mounted at the free end thereof where it is held between a pair of adjusting screws 15 carried by a bracket 16 mounted on the upper part of the yoke Y. The pressure rheostat 4 includes a carbon button 4' or the like stationarily mounted on support 17, and a spring 4" carried by the armature with its contact tip bearing on said button. The wiring shown in connection with this figure is diagrammatic and is believed to be self explanatory.

Referring now to a more elaborate embodiment of the transformer, Fig. 5 shows a U-shaped yoke 20, between the poles N and S of which a centrally pivoted armature 21 is disposed for rotary oscillation on its transverse middle axis and in a plane perpendicular to the plane of said yoke. For this purpose the armature is carried by a pivot shaft 22, the lower end of which rests on a bearing 23 on the middle of the yoke and the upper end of which is held by a bearing 24 carried by an inverted U-bracket 25, the ends of which are secured by means 26 to the polar ends of the yoke. The pressure rheostat 28 is positioned below the armature and the movable contact 29 is carried by the said pivot shaft 22 in effective relation to a stationary contact 30, as will be apparent from Fig. 7. Here the angular displacement of the armature is adjustable by means of a screw 32 carried by an insulated arm 33 on one arm of the yoke and arranged to coact with one end of the leverage spring 34 carried by the pivot post 22, on the opposite end of which spring the movable contact 29 of rheostat 28 is mounted. The said screw, which is arranged to be in tension, is adjusted to swing the armature 21 somewhat out of alignment with the respective yoke poles, so that when an alternating current is applied to the transformer the armature will be caused to vibrate accordingly, thereby also operating the pressure rheostat to render the tertiary winding effective.

The essential connections for this embodiment are substantially like those for Figs. 1 and 4 except that the coils are all duplicated, one set being mounted on each arm of the armature and the corresponding coils being connected in series and wire to a terminal block 36, as will be apparent.

A still further elaborated embodiment is shown by Fig. 6, in which the vibratory armature 40 has four arms 41, instead of two, and on each arm is provided a complete set of coils, primary, secondary and tertiary, the corresponding coils being connected in series, as in Figs. 5 and 8. The yoke 45 is here shown in circular shape,

the plane of which is parallel with the plane of the spider-shaped armature, and four pole pieces 46 are provided thereon corresponding with the poles of the armature. The armature 40 is carried by an upright pivot 48, the ends of which are seated in insulated bearings, such as 23 and 24. The lower bearing is attached to the middle of a cross bar 51 shown fragmentarily in Fig. 6. The upper bearing is attached to the middle of a cross bar or bracket, such as shown at 25 on Fig. 5, the ends of which are secured to a pair of opposite pole pieces, as indicated by the screw holes 53. The armature 40 as a whole is held normally somewhat deflected from the natural position of equilibrium which would be determined by the magnetic pull of the yoke poles 46, the means for accomplishing this being substantially as shown by Figs. 5 and 7, which appears to be quite apparent without further explanation. The circuit connections for the various coils and equipment immediately related to the device in Fig. 6 may be visualized by reference to Fig. 8.

In some instances, as illustrated by Fig. 9, it is preferable to mount the coils on the yoke instead of on the armature, as in Fig. 1. This arrangement diminishes the mass subject to vibration. In this view the pressure rheostat comprises a button member 4 carried by a bracket 55 secured to one pole of the yoke Y and a contact spring 56 therefor is carried by the armature 1, the working position of which is determined by the adjusting screw 1" acting on the spring 1' which is secured to the armature adjacent to its supporting pivot Y'.

In the embodiment shown in Fig. 10, gravity operates in place of a spring to urge the armature 1 away from its natural position as would be determined by magnetic pull alone. An alternating current acting on the primary winding P varies the flux and hence varies the pull on the armature, which accordingly swings vibrantly up and down, thereby producing the desired supplementary effect on the secondary windings to which the loud speaker is connected.

Referring now to the very simple embodiment shown in Fig. 11, the magnetic member is unitary in character and comprises a single bar 58 formed in a loop with the ends disposed adjacent to each other, but with the poles spaced apart slightly to provide an air gap 3 in the characteristic relation of the transformers herein shown. The axes of these poles are displaced somewhat from mutual alinement and the magnetic pull tends to overcome the resilience of the magnetic pair and pull them into alinement. Hence, when an alternating current is applied to the primary

coil P, one of the poles is caused to vibrate relative to the other in accordance with the frequency and intensity of the current impulses. Here the pressure rheostat comprises a button 60 attached to one pole in combination with a spring 61 attached to the other pole for coaction in a circuit including a battery 5 and a tertiary winding, whereby the effect on the secondary winding is amplified.

The operation of my improved transformer, which is essentially electro-mechanical, is substantially the same in each of the several embodiments described. Multiple regeneration is provided for in each instance, either duplex or triplex. With this in view it will suffice to follow through the operation of that assemblage shown in Fig. 3.

When the filament F of tube 8 is energized current flows from the plate battery B through the primary coil A. This augments the flux in transformer 2 and causes the armature 1 to be drawn somewhat closer to the yoke Y against the yielding resistance of spring 1' and thus diminish the air gap 3. Then the changes in the plate current due to tube resistance changes occasioned by a signal or to intake energy on the grid G will cause corresponding vibratory fluctuations in the transformer core flux and consequently will induce currents in the secondary coil B. Furthermore, the physical vibration of armature 1 operates to vary the pressure on rheostat 4 which controls the tertiary winding C, and this supplements coil A and so acts to augment the flux changes and secondaries passing to the sound reproducer, either loud speaker or head phones. The multiple regenerative factors of the transformer may be defined broadly as (1) simple inductive, static, between the primary and secondary windings, (2) dynamo-electric, between said windings, due to mechanical action of the core element or elements, and (3) tertiary, between a rheostat controlled undulatory current winding and the said secondary.

Although several specific embodiments of this invention have been herein shown and described, it is to be understood that no attempt has been made to show or specifically describe all practical embodiments and that some of the details of the constructions shown and described may be altered or amended without departing from the spirit of the invention as defined by the following claims.

I claim:

1. A sound amplifying transformer comprising a magnet having windings thereon adapted and arranged to provide a pair of mutually inductive electrical circuits, said magnet including a pair of relatively mov-

- able core parts included in the magnetic circuit and arranged to provide by their relative movement a variable air gap, and means acting against the magnetic pull which tends
5 to minimize the air gap and mechanically urging said parts to augment said air gap, said core parts being pivotally connected at the core joint separate from said air gap and said resilient means being adjustable.
- 10 2. In a device of the character described, a transformer comprising a permanent magnet mounted stationarily in combination with a vibratorily mounted armature substantially bridging the space between the
15 poles of said magnet, but with a slight variable air gap at one end of said armature, resilient means urging said armature away from its natural position of equilibrium, one of the magnetic members having thereon a
20 primary winding and a secondary winding inductively related thereto.

3. In a device of the character described, a transformer comprising a pair of core members pivotally connected at one point and arranged to provide a small variable air
25 gap when they swing to their normal position of magnetic equilibrium, resilient means urging said members apart to increase said air gap and mutually inductive windings operatively related to the magnetic circuit
30 of said transformer.

4. A transformer comprising open circuit core means having a variable air gap and windings inductively related to said core means, said means being normally disposed in maximum gap conformity and being electromagnetically responsive to one of said windings to minimize said gap.
